UNITED STATES PATENT OFFICE.

JAMES J. SANTIN, OF EL RENO, OKLAHOMA.

DOOR-CHECK.

1,184,215.

Specification of Letters Patent. Patented May 23, 1916.

Application filed August 25, 1915. Serial No. 47,273.

To all whom it may concern:

Be it known that I, JAMES J. SANTIN, a citizen of the United States, residing at El Reno, in the county of Canadian and 5 State of Oklahoma, have invented certain new and useful Improvements in Door-Checks, of which the following is a specification.

This invention relates to door checks and 10 has for its object the provision of a simple, easily applied and efficient device by which the closing movement of a door will be checked or retarded so that slamming of the door will be prevented while positive 15 closing of the same will be accomplished.

A further object of the invention is to provide a door check which will not be dependent upon fluid or liquid pressure and which will, therefore, be inexpensive to 20 maintain, and a still further object of the invention is to provide a device for the stated purpose which may be easily rendered inoperative when so desired.

Other objects of the invention will appear 25 as the description of the same proceeds, and the invention resides in certain novel features which will be particularly pointed out in the claims following the description.

The invention is fully illustrated in the 30 annexed drawing, in which:

Figure 1 is a side elevation of my improved door check, showing the same in its operative position; Fig. 2 is a plan view thereof; Fig. 3 is an enlarged vertical section on the line 3—3 of Fig. 2; Fig. 4 is a section taken on the line 4—4 of Fig. 2; Figs. 5 and 6 are plan views showing different positions of the parts to illustrate the operation; Fig. 7 is a detail perspective view.

In the drawings, the reference numeral 1 40 indicates a swinging door and 2 the frame within which the door is mounted. In carrying out my invention, I secure to the door frame, immediately above the door, a main 45 frame or bracket consisting of a vertical back portion or plate 3 which is adapted to fit directly against the door frame or against the wall and has a forwardly extending horizontal bar or base plate 4 projecting from its 50 lower edge. At the upper end of the back plate or standard 3 is a lug 5 to which is secured a forwardly projecting bar or arm 6 which is adapted to support the upper end of a rotary shaft 7 having its lower end

stepped in the supporting bar 4. If so desired, a cylindrical housing or casing may be secured over the upper keeper arm or bracket 6 by the same rivet 8 which secures said arm to the back plate or standard 3, this casing or housing being indicated in dotted lines 55 at 9 in Fig. 3. The shaft 7 is provided with cylindrical pintles or journals at its ends so that it may rotate easily within the bars 4 and 6 and, immediately above its lower end, it is constructed with an angular portion, shown at 10, which fits within an angular opening in a pinion 11 and a similar opening in a cross bar 12 disposed above the pinion. It will be readily noted, upon reference to Figs. 3 and 4, that the pinion 60 rests upon and is supported by the lower bar 4 and the cross bar 12 may rest directly upon the pinion. The ends of the cross bar 12 are notched or slotted, as shown at 65 13, and in the said notched or slotted portions are pivotally mounted the governor arms 14 which extend upwardly from the 70 said cross bar and are provided at their upper ends with weights 15, as clearly shown. Springs 16 extend between the governor arms 14 and the shaft 7 so as to normally hold the governor arms retracted, as indicated in Fig. 3. The lower ends of the 75 governor arms are turned outwardly, as shown at 17, to provide presser fingers which 80 are adapted to bear upon a brake ring 18 which is secured upon and supported rigidly by the ends of the bar 4. The presser fingers or feet 17 may bear directly upon the 85 brake ring 18, but I prefer to attach to the 90 ends of the cross bar 12 a loosely mounted ring or shoe 19 which extends under the fingers or presser feet 17 so that, when the 95 said feet are thrown downwardly in the operation of the device, the shoe will be forced 100 against the brake band and an extended bearing against the said brake band effected, thereby more effectually retarding the movement of the door and preventing slamming of the same.

The pinion 11 is engaged by a rack bar 20 which is of the peculiar ogee shape shown in Figs. 2, 5 and 6, whereby, as the door swings either to or from the closed position, the rack bar will conform to the angular shifting of the connecting members, and will remain in mesh with the pinion 105 and constantly rotate the same during the

closing movement of the door. The rack bar passes over and is supported by the bar 4 and is held to the bar but permitted a slight lateral play by a pin or other keeper 21 rising from the said bar. As shown most clearly in Fig. 2, one end of the rack is free, while the other end thereof is pivotally connected to a lever 22 having its inner end pivotally supported by a bracket 23 secured to the door 1 at the upper edge thereof. The inner end of this lever is turned downwardly between its pivotal attachment with the bracket 23 and the door so as to present a depending stem or branch 24. A spring 25 is coiled around this depending portion 24 and has its lower end secured to said branch or stem and its upper end secured to the bracket 23 whereby, when the door is opened, the torsional tension of the spring will be increased and the spring will expand or tend to unwind and close the door immediately upon the opening force being removed.

A link or supplemental lever 26 has its outer end pivotally connected to the lever 22 and the rack bar 20 at the point of pivotal connection between said members and the inner end of this link or supplemental lever is pivoted to a bracket 27 secured to the door frame immediately above the door opening and between the plane of the door hinges and the vertical plane occupied by the bracket 23 when the door is closed. The bolt or pin 28, which constitutes the pivotal connection between the levers 22 and 26 and the rack bar 20, projects above the said levers, as shown most clearly in Fig. 4, and a spring 29 is coiled around the said pivot between the link or lever 26 and a nut or washer 30 upon the pivot so as to maintain the pivotal connection between the levers and the rack bar, while at the same time permitting a slight vertical movement of said members so as to prevent the binding and consequent breakage of any of the parts.

It is thought the operation and advantages of the device will be readily understood from the foregoing description taken in connection with the accompanying drawings. The normal position of the parts, with the door closed, is illustrated in Figs. 1 and 2. The initial movement of the door is away from the wall or door frame rather than across or parallel with the same and the lever 22 imparts the same movement to the rack 20 so that the rack will be released from the pinion 11 as shown in Fig. 5. As the opening movement of the door continues, the levers 22 and 26 will, of course, be swung toward the vertical plane of the hinges by which the door is hung upon the door frame, and when the door reaches the position shown in dotted lines in Fig. 5, the pivot 28 will be in a plane between the door frame and a plane parallel thereto passing through

the shaft 7, the rack will extend across the last-named plane at an inclination thereto. The free end of the rack presents a convex edge to the keeper 21 and the engagement of this edge with the keeper swings the end 70 of the rack toward the pinion. The closing movement of the door will initially impart to the rack through the pivot 28 a bodily movement parallel with the face of the door frame so that the rack will be caused to positively engage the pinion and the rack is so shaped that the line of force passing therethrough from the pivot 28 will intersect the pinion and, consequently, hold the rack bar to the pinion. The opening movement of the door will wind the spring 25 and, when the door is released, the spring will at once tend to unwind and through its connection with the lower end of the lever 22 will move said lever and the door toward 80 the normal closed position. The rack will be carried into mesh with the pinion 11 when the door starts to close, as above described, and the pinion will then be rotated during the closing movement. The rotation 90 of the pinion will actuate the shaft 7 and through it swing the cross bar 12 in a horizontal plane. The rotary movement of the cross bar 12 will, of course, carry the governor arms 14 in a circle about the shaft 7 95 as a center and, if the speed of rotation becomes excessive, the tension of the springs 16 will be overcome and the weights 15 will swing outwardly under the action of centrifugal force. When the weights swing 100 outwardly, the arms 14 will, of course, be swung about their pivotal supports and the feet or presser fingers 17 will be moved downwardly so as to press the shoe 19 against the brake band 18. As the brake 105 band 18 is stationary, being secured rigidly to the supporting bracket or frame, the engagement of the shoe with said band will at once create a frictional resistance which will retard the rotation of the shoe and the 110 cross bar 12, the shaft 7 and the pinion 11 to lessen the speed of the rack bar 20 and the closing movement of the door, as will be readily understood.

It will thus be readily seen that I have 115 provided a very simple device which may be applied to any door at a low cost and which will very efficiently resist the closing action of the door so as to prevent slamming of the same and permit the door to close fully but 120 quietly. As my device can be very economically produced and applied, it is especially desirable for attachment to screen doors or other doors which are of light weight. The apparatus will occupy very little space 125 when in use and may be easily applied to either a right hand or left hand door. The parts are all simple and should any one part be broken or damaged through accident or long-continued use, such part may be easily 130

removed and a new part substituted without requiring the provision of an entirely new door check.

Having thus described the invention, what is claimed as new is:

1. The combination of a vertically disposed shaft, a pinion fixed to said shaft, a rack bar adapted to directly engage said pinion, a lever pivotally connected at one end 10 with a door and pivoted at its opposite end to said rack, means acting on said lever to close the door, and a centrifugal device connected with said shaft to retard the closing movement of the door.
2. In a door check, the combination of a bracket adapted to be secured to a door frame, a brake band secured rigidly upon said bracket, a rotary shaft mounted in said bracket, a cross bar carried by said shaft 20 immediately above the brake band, governor arms pivotally mounted in the ends of said cross bar, a brake shoe loosely mounted on the cross bar, presser fingers at the lower ends of the governor arms bearing upon the 25 brake band to carry the same into frictional engagement with the brake band, means for centrifugally moving said governor arms outwardly, a lever adapted to be secured to the door, connections between said lever and said shaft, and a spring connected with said lever and adapted to be placed under tension 30 when the door is opened and to act on said lever and close the door when released.
3. The combination of a shaft, a centrifugal governor connected with the shaft, a pinion on said shaft, a rack bar extending 35

past said pinion and adapted to engage the same, a lever adapted at one end to be pivoted to a door and pivoted at its opposite end to one end of the rack bar, the remaining end 40 of the rack bar being free, a link pivoted at one end to the pivot connecting the rack and the lever and adapted to be pivoted at its opposite end to the door frame above the door, and a spring acting on the lever to 45 close the door.

4. The combination of a shaft, a centrifugal governor connected therewith, a pinion on said shaft, a lever pivoted at one end 50 to a door, a rack of ogee form pivoted at one end to the outer end of the said lever and having its opposite end free, said rack extending past the pinion and adapted to mesh with the same, a link pivoted at one 55 end to the door frame and at its opposite end to the lever and the rack, and a spring acting on the lever to close the door.

5. The combination of a shaft, a centrifugal governor connected therewith, a pinion on said shaft, a lever pivoted at one end 60 to a door, a rack of ogee form pivoted at one end to the outer end of said lever and having its opposite end free, said rack extending past the pinion and adapted to mesh with the same, a keeper holding the rack in 65 the plane of the pinion and permitting lateral bodily movement thereof, a link pivoted at one end to the door frame and at its opposite end to the lever and the rack, and a spring acting on the lever to close the door. 70

In testimony whereof I affix my signature.
JAMES J. SANTIN. [L. S.]
